DESIGN FOR A SHOE OR SIMILAR ARTICLE

Andre Perugia, Paris, France

Application September 22, 1936, Serial No. 64,951

Term of patent 3½ years

To all whom it may concern:

Be it known that I, Andre Perugia, a citizen of Kingdom of Italy, residing in Paris, France, 4 Rue de la Paix, Paris, France, have invented a new, original, and ornamental Design for a Shoe or Similar Article, of which the following is a specification, reference being had to the accompanying drawing, forming part thereof:

Figure 1 is a plan view of a shoe embodying my new design.

Figure 2 is a side perspective view of the shoe. The characteristic feature of the present de-

sign resides in the appearance of the sandal produced by the use of a wide ankle strap attached to each side of the shank of the shoe and crossing the front of the ankle in scarf formation and coming around the heel of the foot and presenting the appearance of a single uninterrupted continuous strap of substantially the same width as the vamp straps.

I claim:

The ornamental design for a shoe or similar article, substantially as shown and described.

ANDRE PERUGIA.
